United States Patent Office.

A. PERIN, OF PARIS, FRANCE.

Letters Patent No. 97,801, dated December 14, 1869,

IMPROVEMENT IN SAW-MILLS.

The Schedule referred to in these Letters Patent and making part of the same.

To all whom it may concern:

Be it known that I, A. PERIN, of Paris, in the Empire of France, have invented a new and improved "Endless-Band Saw" or Resawing-Machine; and do hereby declare that the following description, taken in connection with the accompanying plates of drawings, hereinafter referred to, forms a full and exact specification of the same, wherein I have set forth the nature and principles of my said improvement, by which my invention may be distinguished from others of a similar class, together with such parts as I claim and desire to secure by Letters Patent.

My invention relates to that class of sawing-machines in which a band or belt-saw is made to pass over two pulleys, arranged at a suitable distance apart, by the continuous rotary motion of which, continuous rectilinear motion is imparted to the cutting-part of the saw; and

The nature of my invention consists in certain modifications and improvements in the details of the same, and in certain appliances for the purpose of obviating the difficulties which have heretofore attended the use of endless-band saws, to wit—

First, in accurately adjusting the distance between the pulleys or drums around which the saw-blade passes, imparting a slow rectilinear motion to the carriages, to which are attached the bearings containing the axle-boxes of the said drum, by means of a screw-shaft operated by mitre-wheels.

Second, in the arrangement of an adjustable guide, adaptable to all widths of saws, and capable of either lateral or vertical adjustment.

Third, in the arrangement of an automatic feeding-apparatus, consisting of a system of endless-chain plates and chain-pulleys, connected by a feed-motion, composed of a combination of spur and bevel-gears, with the main driving-shaft of the machine.

Fourth, in the arrangement of the appliances made use of for laterally adjusting the said automatic feeding-apparatus.

Fifth, the arrangement of the devices made use of for the purpose of holding the lumber to be sawed in position, and pressing the same against the plates of the feeder, consisting of a carriage provided with rollers, and actuated by a lever, to which a weight is attached, arranged to slide transversely upon the surface of the table of the machine.

Sixth, in the arrangement of the devices made use of for throwing the pulleys in and out of gear.

In the accompanying plates of drawings, which illustrate my invention, and form a part of the specification thereof—

Figure 1 is a front elevation of a machine embodying my invention.

Figure 2 is a plan of the same.

Figure 3 is an elevation, showing that end of machine which is at the left hand.

The construction of my machine, and relative arrangement of the parts of the same, are as follows, to wit:

Upon the foundation-plate A A, upon which rests the machine, is placed the standard B, which supports the carriage F, to which are secured the bearings E, carrying the two journal-boxes of the upper or tension-pulley. The said standard also forms a support for the bearings G G, carrying the tube H, by means of which the jointed guide e is vertically adjusted.

The carriage F travels upon the angular ways S, and is depressed or raised by means of the screw-shaft d, which is operated by means of the mitre-wheels b and crank a, having its bearings in the said standard B.

The said cylindrical tube H slides vertically in perforations cut for its reception in the bearings g, and is raised or lowered by means of a rack and pinion, operated by the crank u. The said tube is held in position by means of the set-screw f.

To the lower end of the said tube is secured the jointed guide e, consisting of an outer box, e', and an inner box, e''. The said inner box is pivoted or jointed to the outer by means of a pin passing through lugs or flanges projecting from the upper sides of the boxes.

The wooden guide e'', through which the blade of the saw passes, is secured in position within the inner box by means of the set-screw e''', and the required direction is given to the same by means of the rotation of a screw attached to the outer box, and working in a female screw cut in a flange attached to the inner box.

The axle o, of the lower or fixed pulley, revolves in the bearings I, rigidly secured to the standard B, and carries the driving-pulley T, and also a cone of six pulleys, g, which impart motion to a corresponding cone, h, operating the feeding-apparatus.

The said feeding-apparatus consists of a system of plates, K, linked together, and serrated by vertical grooves, and rotating upon chain-pulleys.

Motion is imparted to the said plates by means of spur and bevel-gears i k l m n o p q r, arranged with the axle t, which carries two pulleys, z z', one loose, and the other fixed, over which the belting connecting the same with pulley u is traversed.

The said automatic feeding-apparatus is connected with and supported by the carriage L, sliding within ways, bolted to the table c, and moved laterally by the rotation of the screw-shaft V.

Rotary motion is imparted to the said screw-shaft by the axle x, which passes transversely under the table of the machine, and operates the spur-gears y y'.

The carriage M also slides in ways bolted to the table c, and is provided with rollers, which revolve

upon vertical axes. The said rollers are caused to press hard against the lumber to be cut, by means of the bell-crank or elbow-lever b' , to which is attached the weight c' .

The run of the carriage is limited and adjusted by means of the screw d' , which works in a nut fitted in slots cut at the clevis-shaped end of the short arm of the said lever.

The pulleys upon the main axle O are thrown in and out of gear by means of the slide n , operated by the lever, and the pulleys $z z'$ are thrown in and out of gear by means of the slides P , operated by the lever y .

The lumber to be sawed, having been placed longitudinally upon the table c , is grasped between the rollers of the carriage M and the plates K of the feeding-apparatus. The lever-handle operating the devices for throwing the driving-pulley into gear is then raised, and continuous rotary motion is imparted immediately to the pulleys around which the endless saw passes, which produces the continuous rectilinear motion to that part of the said saw-blade which comes in contact with the lumber.

The operation of the various appliances herein described will be sufficiently indicated by the foregoing description of the same.

Having described the construction, relative arrangement, and operation of my invention, I will designate what I claim as new, and desire to secure by Letters Patent, in the following clauses:

1. The arrangement of the upper or tension-pulley, the carriage E , screw-shaft d , mitre-wheels b , and crank a , when combined, as herein described, with the standard B .

2. The arrangement of the linked serrated plates K , rotating on chain-pulleys, spur and bevel-gears $i k l m n o p q r$, axle t , and pulleys $z z'$, when combined with the carriage L , as herein described.

3. The carriage L , screw-shaft V , axle x , and spur-gears $y y'$, when arranged as described.

4. The arrangement of the carriage M , provided with vertical rollers, elbow-lever b' , weight c' , and screw e , in combination with the table c , as set forth.

5. The jointed guide e , through which the saw-blade passes, when arranged with the cylindrical stem H , substantially as described.

PERIN.
